UNITED STATES PATENT OFFICE.

MARY KAVANAGH, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 15,560, dated November 18, 1884.

Application filed September 12, 1884. Term of patent 3¹/2 years.

To all whom it may concern:

Be it known that I, MARY KAVANAGH, of the city, county, and State of New York, have invented and produced a new and original 5 Design for a Pattern of a Miss's Costume, (numbered 9,416;) and I do hereby declare that the engraved prints accompanying this specification convey to any one accustomed to using paper patterns a clear understanding of how 10 a garment made up by the pattern will appear.

The design shows a walking-skirt and a basque. The skirt displays a deep puff-drapery crossing the front and sides, and exhibiting plaits in its top and a gathering in the 15 lower edge, a deeper puff-drapery at the back exhibiting plaits in its upper, lower, and front

edges, and loopings at the center. The basque displays deep half-fitted jacket-fronts rounding away from the throat over a deep full-puff vest that exhibits gathers at the top and 20 plaits at its lower edge, a shorter close-fitting back outlining two points at its lower edge, coat-sleeves, and a rolling collar.

What I claim as my invention, and desire to secure by Letters Patent, is—

The design for a miss's costume, as shown in the engraved prints accompanying this specification.

MARY KAVANAGH.
